STROPPER ROLL

Frank E. Wolcott, West Hartford, Conn., assignor to Hartford Products Corporation, a corporation of Delaware

Application April 23, 1931, Serial No. 532,251

24 Claims. (Cl. 51—190)

My invention relates to stropers rolls.

It has among its objects to provide an improved stropers roll and improved means for connecting thereto the ends of the stropers strip wound spirally thereon. Further objects of my invention are to provide such a roll of improved structure and having improved means for receiving the ends of the spiral strip, improved holding means co-operating with said means on the roll in holding the ends of the strip securely in position, improved means for strengthening the roll, improved means for preventing relative rotation between the roll and its driving pin, and improved means for positioning the driving gear, all while producing a rugged, simplified and inexpensive construction adapted to be readily and inexpensively assembled. These and other objects and advantages of my improved construction will, however, hereinafter more fully appear.

10 In the accompanying drawing I have shown for purposes of illustration two embodiments which my invention may assume in practice.

In the drawing,—

Figure 1 is a side elevation of a complete roll constructed in accordance with my improvement;

Fig. 2 is a vertical longitudinal sectional view of the same;

Fig. 2a is a detail sectional view on lines 2a—2a of Figure 2.

Fig. 3 is an elevational view of the left hand end of the roll shown in Fig. 1;

Fig. 4 is an end view of the opposite end of the roll;

Fig. 5 is a side elevation of the roll body per se;

Fig. 6 is an end view of the roll shown in Fig. 5;

Fig. 7 is a side elevation showing one end of a modified construction of roll, and

Fig. 8 is an end view of this modified roll.

40 In the construction shown in Figures 1 to 6, I have shown a stropers roll comprising a roll body 1 carrying a spirally disposed stropers leather 2 and having usual journals 3 at its opposite ends and a usual driving gear 4 at one end; this roll herein being of an improved construction and having improved means receiving the ends of the stropers strip 2 and carrying improved means co-operating with said receiving means in holding the parts securely in position, all as hereinafter 50 described.

Referring more particularly to the roll structure, it will be noted that herein, the strip 2 is wound on the outer surface of the roll although obviously it may be wound in a usual spiral groove 55 on the roll, if desired. As shown, the roll at each end is also provided with a longitudinal slot 5 extending across the axis of the roll which preferably, as herein, also has an inclined or sloping inner wall 6, while both of these walls 6 also 60 preferably slope toward the same side of the roll

and in such manner as to produce slots having opposite narrow and wide ends with the narrow ends on one side of the roll and the wider ends diametrically opposite the same. Moreover, it will be noted that each slotted end of the roll is herein, as preferably, reduced as shown at 7, each reduced portion herein having at its inner end the usual annular groove incident to its manufacture. It will also be noted that each end of the roll is provided with an axial bore adapted to receive 70 the pins 8 and 9 carrying the journals 3. As shown, one of these bores 10 is short, while the other, 11, which receives the driving pin 9 carrying the gear 4, is longer than the bore 10 and of two diameters (Fig. 5) and provided with a reduced extension 12 adapted to receive longitudinally and thereafter hold against rotation, a flattened end portion 13 on the pin 9. Obviously, if desired, similar extensions may be provided in the end of the bore 10 and on the end of the 80 pin 8, but these are ordinarily omitted since the pin 8 is not a part of the driving train.

Referring more particularly to the connections for the leather strip 2, it will be noted that in this construction the leather 2 is held in place 85 wholly independent of the pins 8 and 9. More particularly, it will be noted that the bent ends of the leather strip, indicated at 14, are extended through the wide ends of the slots 5 in such manner that they do not extend into the 90 axial bores 10 and 11. Moreover, it will be noted that a ferrule 15 is driven down over each reduced end 7 of the roll and into the outer sides of the inturned ends 14 of the strip 2 in such manner as not only to press the opposite sides 95 of the ends 14 tight against the walls 6, but also, through the slight penetration of the inner edge of the ferrule into the leather, as shown in Figure 2, securely hold the latter in position when the outer end of the ferrule is overturned, 100 as shown at 16 in Figure 3 around the periphery of the end face 17 of the reduced portion 7. As shown, this portion 16 is preferably in the form of a narrow peripheral band and also engaged at one end of the roll by the periphery 105 of the gear 4 which is clamped by the pin 9 between the end of the roll on one side and the journal on the other. It will also be noted that at the same time that the ferrule 15 thus forces the extension 14 inward in the wide end of the slot 5, the ferrule acts to cover the narrow end of the slot 5 in such manner as to produce a finished construction, while, the body of the ferrule being disposed in the reduced portion 7, the ferrule also acts to produce a finished roll 110 of uniform diameter from end to end and of attractive appearance.

In Figures 7 and 8 I have shown a modified construction, which, while not preferred, may be used if desired. In this construction it will be 115 120

noted that, instead of the slot 5, a transverse aperture 18, herein in the form of a round hole, is provided at the junction of the reduced portion 7 with the body 1, and part in each. In 5 this construction, the ends 14 of the leather strip 2 are extended into these apertures in the same manner previously described, while the ferrule 15 engages and positions the ends 14 in the same manner as previously described. Obviously 10 this construction will also function similarly to that previously described. Also, by providing an aperture 18 only extending from the periphery into the bore, a construction may be provided which presents no unused aperture in 15 the periphery of the finished roll, while, by using a longer aperture which extends completely through the roll, a reversible construction will be provided which will receive the ends 14 in either end thereof and require the presence of 20 only a relatively small unused aperture in the surface of the roll.

As a result of my improved construction, it is made possible to provide a roll structure which may be assembled as a unit with its leather strip 25 fixed in position prior to the insertion of the pins therein, and in which, the pins being independent of the holding means for the leather, the insertion of the pins can in no way disturb or shift the leather strip. Moreover, it will be 30 noted that while I am not limited to the use of a particular material for the body of the roll, the construction is such as to lend itself readily to use with a wooden roll body, the presence of the ferrules acting to strengthen the roll and 35 acting to minimize any tendency to split. It will also be noted that the ends of the strip 2 are so securely positioned by the ferrules and the co-operating openings in the ends of the roll, as to enable the strip 2 to be very tight on the roll 40 periphery and accordingly permit a roll of uniform external diameter to be used without grooving or holding means, with a minimum of slipping possible on the part of the strip 2. Obviously, also, in my improved construction it will 45 be noted that due to the interlock of the aperture 12 with the end 13 of the pin 9, which carries the gear 4, this driving pin is securely positioned against rotation relative to the roll, at the same time that the gear is securely held 50 between the bearing 3 on the pin and the adjacent peripheral portion 16 on the ferrule 15, and reliance upon the engagement of the body of the pin with the bore is so minimized as to permit a smooth or unfluted pin to be used if desired. 55 Attention is also directed to the fact that the roll body per se is of such construction as to be very readily and cheaply made and also such as to permit the use of wood if desired. Attention is further directed to the fact that the structure of the component parts is such that the complete roll may be manufactured and assembled at small expense, while providing a very effective construction adapted to withstand long use in 60 service. These and other advantages of my improved construction will, however, be clearly apparent to those skilled in the art.

While I have in this application specifically described two embodiments which my invention 70 may assume in practice, it will be understood that the same are shown for purposes of illustration only, and that the invention is not limited thereto but may be modified and embodied in various other forms without departing from its 75 spirit or the scope of the appended claims.

What I claim as new and desire to secure by Letters Patent is:—

1. A stropper roll having an aperture in its body extending transversely thereof from the periphery of its end, a sharpening strip wound spirally on the periphery of said body and having an end extending into said aperture, and a ferrule having a driving fit on the periphery of said roll end pressing the end of said strip against the inner wall of said aperture. 80

2. A stropper roll having an aperture in its body extending transversely thereof from the periphery of its end, a sharpening strip wound spirally on the periphery of said body and having an end extending into said aperture, and a ferrule, said roll body having a reduced end and said ferrule having a driving fit on said reduced end and pressing said end of said strip against the inner wall of said aperture. 85

3. A stropper roll having an aperture in its body extending transversely thereof from the periphery of its end and an axial bore, a pin in said bore, a stropper strip wound spirally on the periphery of said roll and having a bent end in said aperture, and means independent of said pin for positioning said bent end in said aperture. 90

4. A stropper roll having an aperture in its body extending transversely thereof from the periphery of its end and an axial bore, a pin in said bore, a stropper strip spirally disposed on the periphery of said roll and having a bent end in said aperture, and a ferrule independent of said pin for positioning said bent end in said aperture. 105

5. A stropper roll having a transverse slot extending across its end and also an axial bore, a pin in said bore, a stropper strip spirally wound on the periphery of said roll body and having a bent end in said slot, and means independent of said pin and overlying said slot on the roll periphery for positioning said bent end in said slot. 110

6. A stropper roll having a transverse slot extending across its end and also an axial bore, a pin in said bore, a stropper strip wound spirally on the periphery of said roll and having a bent end in said slot, and a ferrule independent of said pin and overlying said slot on the roll periphery for positioning said bent end in said slot. 120

7. A stropper roll having a transversely disposed aperture in its end and an axial bore, a pin in said bore, a spirally wound stropper member having a bent end in said aperture, and means independent of said pin and driven on said roll for pressing said bent end in said aperture longitudinally of said roll. 125

8. A stropper roll having a transversely disposed aperture in its end and an axial bore, a pin in said bore, a spirally wound stropper member having a bent end in said aperture, and a ferrule independent of said pin and driven on the periphery of said roll for pressing said bent end in 130 said aperture longitudinally of said roll.

9. A stropper roll having a transverse slot extending across its end and also an axial bore, a pin in said bore, a spirally wound stropper member having a bent end in said slot, and a ferrule independent of said pin for positioning said bent end in said slot, said slot having an inclined inner wall and having its unused end covered by said ferrule. 140

10. A stropper roll having an aperture in its end and an axial bore, a pin in said bore, a spirally wound stropper member having a bent end in said aperture, and a ferrule independent of said pin for positioning said bent end in said aperture and having a peripheral portion engaging the end of 145

- said roll and an enlarged axial aperture surrounding said pin.
11. A stropper roll having an aperture in its body extending transversely thereof from the 5 periphery of its end and an axial bore, a pin in said bore, a stropper strip wound spirally on the periphery of said roll and having a bent end in said aperture, a ferrule overlying said aperture on the roll periphery and positioning said bent 10 end in said aperture, and a gear carried on said pin and clamped thereby against said ferrule. 80
12. A stropper roll having an axial aperture therein and a rigid journal pin having a driving fit in said aperture having driven means embedded in the side walls of the latter and an 15 inner extremity, and co-operating interlocking means in the inner end wall of said aperture and on said inner extremity of said pin interlocking when said pin is driven into said aperture to 20 prevent relative rotation between said roll and pin. 85
13. A stropper roll having an axial aperture therein and a journal pin having a driving fit in said aperture, and co-operating interlocking 25 means respectively integral with the inner end wall of said aperture and integral with the inner end of said pin interlocking to prevent relative rotation between said roll and pin when said pin is driven into said aperture, said interlocking 30 means being longitudinally connectible and comprising an extension on said pin and an extension in said bore receiving said first extension. 90
14. A stropper roll having a wooden body and an axial bore, a journal pin having a driving fit 35 in said bore insertable therein without rotation relative to the latter and having driven means embedded in the side wall of said bore, and longitudinally connectible interlocking means interlocking when said pin is driven into said aperture preventing relative rotation between said 40 pin and roll and comprising interfitting portions at the inner end of said pin and bore and integral with the end wall of said bore and the extremity of said pin. 100
15. A stropper roll having an axial bore, a journal pin in said bore having a driving fit therein and driven means imbedded in the side walls of 45 said bore, longitudinally connectible interlocking means preventing relative rotation between said pin and roll located at the inner end of said pin and bore and automatically connectible when said pin is driven into said bore, a ferrule having a driving fit on the end of said roll, and a gear clamped between the outer ends of said pin 50 and ferrule. 110
16. A stropper roll having an axial bore, a pin in said bore insertable therein without rotation relative to the latter, longitudinally connectible 60 interlocking means preventing relative rotation between said pin and roll located at the inner end of said pin and bore, a ferrule carried on the end of said roll, and a gear disposed between the outer ends of said pin and ferrule, said roll having a transverse aperture in its end and a spirally 65 wound stropping member having a bent end in said aperture and positioned therein by said ferrule. 120
17. A stropper roll having an axial bore, a pin in said bore, insertable therein without rotation 70 relative to the latter, longitudinally connectible interlocking means preventing relative rotation between said pin and roll located at the inner end of said pin and bore, a ferrule carried on the end of said roll, and a gear disposed between the 75 end of said roll, and a gear disposed between the 80
- outer ends of said pin and ferrule, said roll having a transverse slot having an inclined inner wall and a spirally wound stropping element having a bent end in the wider end of said slot and positioned by said ferrule. 85
18. A stropper roll having a wooden body, an axial bore therein, and a transverse aperture leading from the roll periphery toward said bore, a stropper strip wound spirally on said roll and having an end in said aperture, a journal pin driven in said bore and having portions embedded in the wall thereof, and a peripheral ferrule on the roll end inhibiting splitting of the roll body by said pin and also positioning said end in said aperture. 90
19. A roll for supporting a stropper strip, having an axial bore, a reduced portion surrounding one end of the same, and a slot extending transversely of said reduced portion on each side of said bore and also extending longitudinally into the unreduced portion of said roll at one side of said bore, said last mentioned portion of the slot being adapted to receive the end of a stropper strip and said reduced portion being adapted to receive positioning means for said strip end. 95
20. A roll for supporting a stropper strip, having an axial bore, a reduced portion surrounding one end of the same, and a slot extending transversely of said reduced portion on each side of said bore and also extending longitudinally into the unreduced portion of said roll at one side of said bore and having an inclined transversely disposed inner wall reducing the depth of one end of said slot, said slot being adapted to receive the end of a stropper strip in its wider end and said reduced 100 portion being adapted to receive positioning means for said strip end. 105
21. A roll for supporting a stropper strip, having an axial bore in its end and a slot in said end extending diametrically across the roll end and having an inclined inner wall producing slots of different lengths in the periphery of the end of the roll and disposed longitudinally of the latter on opposite sides of said bore, the slot of longer length being adapted to receive the end of a 110 stropper strip. 115
22. A roll for supporting a stropper strip, having an axial bore, a reduced portion surrounding one end of the same, and a transverse aperture spaced from the extremity of said reduced portion and communicating with said aperture, said transverse aperture being adapted to receive the end of a stropper strip and said reduced portion being adapted to receive positioning means for said strip end. 120
23. A roll for supporting a stropper strip, having an axial bore, a reduced portion surrounding one end of the same, and a transverse aperture spaced from the extremity of said reduced portion and communicating with said aperture, said aperture being disposed in part in each of the reduced and unreduced portions of the roll, said transverse aperture being adapted to receive the end of a stropper strip in the unreduced portion of the roll and said reduced portion being adapted 125 to receive positioning means for said strip end. 130
24. A driving journal pin for stropper rolls having a journal portion on one end thereof, an elongated peripherally roughened intermediate driving portion of smaller diameter than said journal 140 portion, and rotation inhibiting means at its opposite extremity comprising a plurality of flattened portions on opposite sides of said extremity. 135
